UNITED STATES PATENT OFFICE.

ARTHUR SIMON, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,318,508.

Specification of Letters Patent.

Patented Oct. 14, 1919.

Application filed April 19, 1911. Serial No. 622,089.

To all whom it may concern:

Be it known that I, ARTHUR SIMON, a citizen of the United States, residing at Milwaukee, in the county of Milwaukee and 5 State of Wisconsin, have invented new and useful Improvements in Electric Switches, of which the following is a full, clear, concise, and exact description, reference being had to the accompanying drawing, forming 10 a part of this specification.

My invention relates to improvements in electric switches.

My invention relates particularly to switches to be immersed in oil, but is not 15 limited to this particular class of switches.

In oil immersed switches it is very desirable to secure a horizontal break of the circuit controlled thereby, that is to say it is desirable to have the switch so designed that 20 the arc drawn between its contacts will be disposed in a substantial horizontal plane. The desirability of this form of break is due to the fact that it greatly facilitates and expedites the rupture or expenditure of 25 the arcs produced. Where a vertical break is provided, that is where the arc is drawn vertically, the oil in which the switch is immersed forms a pocket which so confines the arc as to prolong the duration of its 30 existence. On the other hand where the arc is drawn horizontally it has a tendency to bow or stretch upwardly and thereby quickly disrupt itself meeting with but comparatively small resistance from the oil.

35 It is one of the objects of my invention to provide a switch which will give this form of break, and to so construct the same as to enable it to be operated by a longitudinally movable member preferably a vertically 40 movable member in order that said member may be extended through the top of the oil casing.

Various other objects and advantages of my invention will be hereinafter clearly and 45 fully set forth.

In order to more fully and clearly set forth the nature and characteristic features of my invention I shall describe the embodiment thereof illustrated in the accompanying drawing. It should be understood that my invention is not limited to the specific embodiment thereof which I have illustrated in the accompanying drawings, and that the

accompanying drawings should be considered as illustrative only and not as limiting 55 the scope of my invention.

In the accompanying drawings Figure 1 is a side elevation of the switch.

Fig. 2 is a sectional view taken on line 2—2 Fig. 1.

Figs. 3 and 4 are enlarged detail views, the former partially in section, of a portion of the switch and

Fig. 5 is a sectional view taken on line 5—5 Fig. 3.

The various parts of the structure illustrated are supported by a suitable frame or plate which in turn is provided on opposite sides with lugs 2, to facilitate the mounting thereof on suitable standards. On the under 70 side of the member 1 and in proximity to the corners thereof are four blocks 3, preferably formed integrally therewith. Two of the blocks 3 are clearly illustrated in Fig. 2. Suitably secured to the blocks 3 on opposite sides of the member 1 are inverted U shaped brackets, one of which is shown in dotted lines in Fig. 1. These brackets are preferably formed of cast iron to give the same the required strength and rigidity. 75 Each bracket is provided at its lower end with cross members 5 and 5^a, preferably comprising wooden bars secured to said brackets by suitable means such as bolts 6. The wooden cross members 5 form supports 80 for the switch members which I shall now describe.

The switch illustrated is of the triple pole type in which each line controlled thereby is broken at two points. Accordingly there are provided six switches constituting three pairs one pair for each line. The switches of each pair are mounted directly opposite one another. The switches are all of the same construction so that it 90 will suffice to describe only one of the same.

As will be seen from Fig. 2 each of the switches comprises essentially a pivoted rigid arm 7 carrying a main contact 8 and an arcing contact 9, said contacts to engage 100 a relatively stationary laminated main contact brush 10, and a relatively stationary arcing contact 11 respectively. The contact arm 7 is pivoted to move in a vertical plane and the contacts are so arranged that upon 105 the contact arm 7, leaving the relatively sta-

tionary contacts, the arc produced thereby will be drawn horizontally with the advantageous results above pointed out.

Referring now to Figs. 3, 4 and 5, I will give a more detailed description of the switches. The arm 7 is pivoted at 12 to a bracket 13 which is secured to the wooden cross bar 5 by bolts 14. The bracket 13 is provided at its bottom with a lug 15 carrying a binding post 16 to which is adapted to be connected one of the circuit leads. Also connected to the binding post 16 is a short lead 18 secured by means of a screw 19 to the arm 7. The main contact 8 on the arm 7 preferably comprises a flat plate secured to said arm by a bolt or bolts 20. The stationary contacts of the switch are mounted upon the wooden cross member 5. Secured on the top of this cross member preferably by bolts 21 is an angle plate 22 having on its forward extremity a suitable seat for the main laminated brush 10 which is secured thereto by a bolt 23. Also at its forward end the angle plate 22 is provided with a suitable support for the pivoted arm 24 carrying the arcing contact 11. The upright portion of the angle plate carries a bolt 25 which extends through the arm 24 and has its head within a recess in said arm. Surrounding the bolt 25 and interposed between the angle plate 22 and the arm 24 is a helical spring 26 which tends to force the arm 24 toward the contact arm 7. Both the arm 24 and the main contact brush 10 are electrically connected to the angle plate 22 which at its upper end is provided with a suitable binding post 27 for line connection.

The arcing contacts 9 and 11 preferably comprise heavy copper shoes with enlarged curved surfaces which tend to guide the arc drawn between the same in an upward direction at the same time stretching and cooling the same. Also they prevent the accumulation of oil between the same.

The operation of the switch is apparent from Figs. 3 and 4 in which it will be seen that due to the action of the spring 26 the arcing contacts will be the first to engage when the switch is closed and the last to disengage when the switch is opened. After the auxiliary contacts have been brought into engagement continued movement of the arm 7 causes the main contact plate carried thereby to engage the main contact brush 10, the arcing contact arm 24 in the meantime being forced rearwardly against the spring 26.

As above stated all of the switches are of the same construction. In a multiple switch device of this character it is desirable to have all of the switches actuated simultaneously. I have provided means for accomplishing this operation of the switches which may be readily adapted to either

manual or power operation. For the purpose of this application I have shown the same adapted for power operation. I shall now describe the operating means illustrated.

For each pair of switches I have provided a vertically movable rod 30 extending down through the top of the casing to a point midway between the switches. All three of these rods are shown in Fig. 1, and one of the same is illustrated in Fig. 2. Each of the rods 30 is provided at its lower extremity with a cross member 31, the opposite ends of which are operatively connected to the two switches to be actuated thereby in the following manner. The connections for both switches being identical I shall only describe one of the same. These connections are best illustrated in Figs. 3, 4 and 5. They consist of a link 33 pivoted at one end to the upper extremity of the bracket 13 and at its opposite end to the cross member 31 of the rod 30. The pivot pin 34 which connects the link 33 to the cross member 31 preferably works in slots 35 provided in said cross member whereby the rod 30 will be relieved of any lateral strain to which it would otherwise be subjected upon turning the link 33 about the pivot at the opposite end thereof. The link 33 is connected to the contact arm 7 by an intermediate link 36 pivoted at one end on a pin 37 carried by said link and on its opposite end on a pin 38 carried by a lug 39 on the arm 7. In practice in order to secure compactness and at the same time strength and rigidity I prefer to bifurcate the cross member 31 and the links 33 and 36, placing one inside of the other.

With the connections just described it will be seen that when the rod 30 and cross member 31 are raised the outer end of the link 33 will be raised and will through the intermediate link 36 force the arm 7 inwardly into engagement with its stationary contacts in the manner previously described. On the other hand when the rod 30 descends it moves the link 33 in the opposite direction thereby releasing the contact arm 7. The parts of the structure being of considerable weight and returning to normal position by gravity I preferably provide in the contact arm 7 a spring buffer 40 adapted to be engaged by a lug 41 on the link 36 to prevent an undue shock to the parts. As previously set forth the two switches of each set are connected in a similar manner to the same operating rod, and accordingly operate simultaneously.

Each of the operating rods 30 is provided at its upper end with a cap 43 all of which caps are connected preferably by means of pins 44 to a cross member 45. The cross member 45 may be actuated to simultaneously move all of the rods either manually

or by power. As illustrated I have shown this cross member operated by a solenoid S. The solenoid is mounted in a suitable frame 47 having standards 48 bolted to the supporting member 1. This solenoid has two coils arranged side by side and provided with a U-shaped plunger 49 to which the cross member 45 is secured. The cross member 45 is provided with an upwardly projecting rod 50 which extends through the U-shaped plunger 49 and also through the bottom of the frame 47. This rod is rigidly secured to the plunger 49 as by a pin 51 and is provided at its upper end with adjustable nuts 52. Due to the fact that the member 45 is rigidly connected to the plunger 49 it will be observed that when the solenoid is energized the cross member 45 will move with the plunger 49 raising all of the rods 30 and thereby simultaneously actuating all of the switches, and that upon deenergization of the solenoid the plunger 49 and cross member 45 will drop back to initial position. The nuts 52 on the rod 50 by engagement with the magnet frame will limit the downward movement of the plunger and cross member 45, and consequently the degree of opening of the switches. Obviously by adjustment of the nuts 52 the range of movement of the parts may be varied as desired. The rod 50 also serves to operate auxiliary switches 53 which may be utilized for any desired purpose.

For inclosing the switches I have shown a tank or receptacle 54 adapted to contain oil for immersion of the switches. This tank is in the form of a box and provided on opposite sides with pivoted bolts 55 upon which are mounted wing nuts 56 adapted to engage with lugs or ears 57 on the member 1 to support said tank in position. This form of retaining means allows the tank 54 to be lowered to give access to the switch mechanism without in any wise disturbing the same. Of course in practice each pair of switches might be provided with a separate oil tank if desired.

In order to facilitate raising the oil receptacle 54, I preferably provide the same with counter-weights on one end of chains which pass over the sprocket pulleys and are fixed to the cover frame 1, as shown in Fig. 1.

What I claim as new and desire to secure by Letters Patent is as follows:

1. An oil immersed switch comprising, in combination, a casing, a switch support suspended therein from the casing cover, a stationary contact carried by said support, a vertically disposed switch arm pivoted to said support and having at its upper end a co-operating contact, a reciprocable operating rod extending through the casing cover, an operative connection between said rod and said switch arm, and electromagnetic means carried by the casing cover but above

the same for controlling movement of said rod.

2. In combination, an oil receptacle, a stationary member suspended therein, a vertically disposed arm pivoted to said stationary member, a main contact and an arcing contact carried thereby, both of said contacts having vertically disposed active faces at right angles to the plane in which said arm moves, a stationary laminated brush mounted on said stationary member to be engaged by said main contact and a contact pivoted to said stationary member to be engaged by said arcing contact.

3. In combination, an oil receptacle, a stationary member suspended therein, a vertically disposed arm pivoted to said stationary member, a main contact and an arcing contact carried thereby, both of said contacts having vertically disposed active faces at right angles to the plane in which said arm moves, a stationary laminated brush mounted on said stationary member to be engaged by said main contact and a contact pivoted to said stationary member to be engaged by said arcing contact, said arcing contacts being arranged above said main contacts and having engaging surfaces diverging from the points of contact.

4. In combination, an oil receptacle, a bracket suspended therein, a vertically disposed and upwardly projecting switch mounted upon said bracket and provided at its upper extremity with abutment arcing contacts having vertically disposed co-operating faces and means operable from the outside of said receptacle to actuate said switch to move said contacts into and out of engagement.

5. In combination, an oil receptacle, a bracket suspended therein, a vertically disposed and upwardly projecting switch mounted upon said bracket and having at its upper end vertically disposed co-operating contacts and a reciprocating member projecting downwardly through the top of said receptacle and connected to said switch to operate the same.

6. In combination, an oil receptacle, a bracket suspended therein, a vertically disposed and upwardly projecting switch mounted upon said bracket and having at its upper end vertically disposed co-operating contacts and a reciprocating member projecting downwardly through the top of said receptacle and an operative connection between said reciprocating member and said switch comprising a toggle.

7. In combination, an oil receptacle, brackets suspended therein, vertically disposed and upwardly projecting switches mounted upon said brackets in the same vertical plane, each of said switches having at its upper end vertically disposed co-operating contacts and a reciprocating mem-

- ber projecting into said receptacle between said switches, and operatively connected to said switches to simultaneously operate the same.
- 5 8. In combination, a horizontal support, an oil containing receptacle suspended from said support, a pair of brackets depending from said support and extending into said receptacle, a pair of vertically disposed and
- 10 upwardly projecting switches mounted upon said brackets and each provided at its upper end with vertically disposed coöperat-
- ing contacts and a reciprocating member projecting into said receptacle through said support and toggle operating connections 15 between said member and said switches.
- In witness whereof I have hereunto subscribed my name in the presence of two witnesses.

ARTHUR SIMON.
